CORNER GRINDING MACHINE

Peter J. Kirkman, Ottawa, Ill., assignor to Libbey-Owens-Ford Glass Company, Toledo, Ohio, a corporation of Ohio

Application May 14, 1940, Serial No. 335,092

4 Claims. (Cl. 51—80)

The present invention relates to grinding machines in general and more particularly to an improved machine for grinding the corners of sheets or plates of glass and the like to remove the rough or sharp edges thereof and obtain smooth, well finished surfaces.

An important object of the invention is the provision of a machine of the above character effective for grinding two opposite corners of the glass sheets or plates simultaneously in a rapid, accurate, and economical manner.

Another important object of the invention is the provision of a machine of the above character which is of relatively simple, inexpensive construction, yet positive and efficient in operation and which will serve to grind the opposite corners of the glass sheets or plates evenly and uniformly.

Other objects and advantages of the invention will become more apparent during the course of the following description when taken in connection with the accompanying drawings.

In the drawings wherein like numerals are employed to designate like parts throughout the same:

Fig. 1 is a side elevation, partially in section, of a corner grinding machine constructed in accordance with this invention;

Fig. 2 is an end view of the machine, partially in section;

Fig. 3 is a rear view of the machine; and

Fig. 4 is a detail plan view of the means for supporting the glass sheets or plates during grinding.

With reference now to the drawings, the grinding machine comprises a stationary supporting framework 10 upon which are mounted the vertical grinding wheels 11 and 12. The grinding wheels are horizontally spaced from one another and positioned to rotate about horizontal axes, each grinding wheel being preferably provided in its periphery with a plurality of grooves 13 for receiving the corners of the sheets or plates of glass or the like 14 to be ground. The glass sheets 14 are supported on edge in a vertical position above the grinding wheels 11 and 12 by horizontal supporting means designated in its entirety by the numeral 15.

The grinding wheels 11 and 12 are maintained in relatively fixed position during the grinding operation, while the glass sheets 14 are moved downwardly to bring the two opposite corners *a* and *b* thereof to be ground into engagement with the grinding wheels 11 and 12 respectively whereby to effect the simultaneous rounding of

said corners, as indicated in broken lines in Fig. 1. Thus, the corners *a* of the glass sheets are received in the grooves 13 of grinding wheel 11 and the corners *b* in the grooves of grinding wheel 12. After the glass sheets have been properly ground, they are moved upwardly out of engagement with the grinding wheels as shown in full lines in Fig. 1, whereupon they are removed and another group of sheets to be treated brought into position for grinding.

More specifically, the supporting frame 10 is preferably substantially rectangular both in side elevation and top plan and comprises the spaced vertical legs 16—16 at one end thereof and similar legs 17—17 at the opposite end. Extending between and carried by the pair of legs at each end of the supporting frame 10 is a horizontal transverse member 18, while extending longitudinally of the frame and carried by the opposed legs 16 and 17 are the horizontal members 19 and 20 supported intermediate their ends by vertical legs 21—21. Carried upon the top of the longitudinally extending members 19 and 20 are the stationary rails or slides 22 and 23 respectively for supporting the grinding units A and B which include the grinding wheels 11 and 12 respectively.

The grinding wheel 11 of grinding unit A is mounted upon one end of a horizontal shaft 24 journaled in spaced bearings 25 and 26 carried by horizontal base plates 27 and 28 which are slidable along the fixed rails 22 and 23 respectively. Also mounted upon the base plate 28 is a motor 29 for driving the grinding wheel 11. To this end, the shaft 30 of motor 29 has keyed thereto a gear 31 meshing with a gear 32 fixed to the shaft 24 of grinding wheel 11. Upon operation of the motor 29, rotation will be imparted to the grinding wheel 11 through the intermeshing gears 31 and 32.

The grinding unit B is of substantially the same construction as grinding unit A, and to this end the grinding wheel 12 thereof is keyed to one end of a horizontal shaft 33 mounted in spaced bearings which are slidable along the rails 22 and 23 in the same manner as the bearings 25 and 26 of grinding unit A. The shaft 33 of grinding wheel 12 is driven from a motor 34 also through intermeshing gears (not shown).

The grinding units A and B are preferably adjustable horizontally toward and away from one another to vary the distance between the grinding wheels 11 and 12 according to the size of glass sheets being ground. This adjustment may be effected manually in the following manner:

As shown in Figs. 2 and 3, there is provided at the outer end of the base plate 28 slidable along rail 23 a vertical ear 35, while carried by the supporting frame 10, in alignment with said ear, 5 is a bearing 36. Threaded through the bearing 36 and having its inner end rotatably secured within ear 35 is a horizontal adjusting screw 37 provided at its outer end with an operating handle 38 to facilitate rotation thereof.

10 As will be apparent, upon turning of the handle 38 to rotate screw 37, the base plate 28 and motor 29 carried thereby can be moved inwardly or outwardly as desired along rail 23. In order to effect simultaneous movement of the corresponding base plate 27 along rail 22, there is carried by said base plate an ear 39 similar to ear 35 on base plate 28, while a bearing similar to bearing 36 is carried by the supporting framework 10. Associated with the ear 39 and corresponding bearing is a horizontal adjusting screw 40 similar to screw 37. Carried by the adjusting screws 37 and 40 are sprockets 41 and 42 respectively about which is trained a sprocket chain 43 which serves to impart rotation of screw 37 to screw 40. In this 25 way, the base plates 27 and 28 can be moved in unison along the rails 22 and 23 to properly position the grinding wheel 11.

The grinding unit B can be similarly adjusted along the rails 22 and 23 by means of the horizontal adjusting screws 44 and 45 carrying sprockets 46 and 47 respectively about which is trained a sprocket chain 48. Each adjusting screw 44 and 45 is carried at one end by a sleeve 49 rotatable in the upper end of a bracket 50 secured to the respective rail 22 or 23, while the opposite end of said screw is threaded through a nut 51 carried at the upper end of a bracket 52 secured to the respective base plate 28 or 29. One of the adjusting screws, for example screw 44, is provided with an operating handle 53 and, upon rotation thereof, the motor 34 and grinding wheel 12 can be moved in unison along the rails 22 and 23.

The supporting means 15 for the glass sheets or plates 14 comprises a longitudinally extending, U-shaped channel member 54 having a bottom 55 and vertical side walls 56 and 57, said channel member being carried at the opposite ends of the supporting frame 10 from standards or the like 58 and 59. Mounted within the channel member 54 between the grinding wheels 11 and 12 is a vertically movable, horizontal platform 60 carrying a mat 61 preferably of rubber, rubber composition, or the like, and provided upon its upper surface with a plurality of grooves 62 for receiving the bottom edges of the glass sheets 14 therein. The bottom 55 of channel member 54 is cut away above the grinding wheels 11 and 12, as indicated at 63, so that the horizontal platform 60 can be moved vertically to assume either the upper full line position or the lowered broken line position in Fig. 1. For the purpose of guiding the platform 60 in its vertical movements, it is provided at each side thereof and at its opposite ends with outwardly directed ears 64 and 65 slidable within vertical guideways formed by the in-turned flanges 66 and 67 carried by and disposed inwardly of and parallel with the side walls 56 and 57 of the channel member 54.

70 Arranged within the channel member 54 at one side of the platform 60 is a series of horizontally aligned conveyor rollers 68 and at the opposite side thereof a series of similar conveyor rollers 69, said rollers 68 and 69 being also 75 preferably provided with grooves which are

adapted to align with the grooves 62 in the platform 60 when said platform is in raised position. In this manner, the glass sheets 14 to be ground can be moved along the rollers 68 onto the platform 60 and after being ground can be pushed 8 from said platform onto the rollers 69.

The sheet supporting platform 60 is normally urged upwardly into its full line inoperative position in Fig. 1 and is adapted to be moved downwardly by the operator when it is desired to effect 10 the grinding of the corners *a* and *b* of the glass sheets. To accomplish this, there is provided a substantially horizontal foot lever 70 pivoted at its rear end as at 71 to the framework 10 and provided at its forward end with a foot pedal 72. 15 Carried by the sheet supporting platform 60 is a depending rod 73 connected at its lower end by means of a turn-buckle 74, with a second rod 75 pivoted at its lower end as at 76 to the foot lever 70. Upon downward pressure upon the foot pedal 20 72, the platform 60 and glass sheets 14 thereon will be moved to lowered grinding position, while upon release of such pressure the said platform is automatically returned to and maintained in raised position by tension springs 77 and 78 secured at their lower ends to the foot lever 70 and at their upper ends to the side walls 56 and 57 of channel member 54. The amount of material removed from the corners *a* and *b* of the glass sheets when moved to lowered position or, in 25 other words, the extent of the grinding operation can be varied by controlling the length of time the glass sheets are engaged with the grinding wheels and the pressure of the glass against said wheels. 35

The grinding apparatus herein provided can be used either in connection with the so-called Weber type of edging machine to receive the glass sheets therefrom or it can be employed by itself as an individual machine. If the grinding apparatus is arranged at the end of a Weber type machine to receive the glass sheets therefrom, the conveyor rollers 68 should be arranged in horizontal alignment with the conveyor rollers of said Weber machine. After the corners *a* and *b* 45 of the glass sheets 14 have been properly ground, the sheets can then be moved over the conveyor rollers 69 to the desired location or to another machine where the sheets can be further treated.

It is to be understood that the form of the invention herewith shown and described is to be taken as the preferred embodiment of the same, and that various changes in the shape, size and arrangement of parts may be resorted to without departing from the spirit of the invention or the 55 scope of the subjoined claims.

I claim:

1. In a machine for grinding the corners of sheets or plates of glass and the like, a vertically movable horizontal platform for supporting the 60 sheet to be ground on edge in a vertical position, horizontal conveyor means arranged at opposite sides of said platform and along which the sheet may be moved onto the platform prior to grinding, and from said platform subsequent to grinding, a pair of rotatable grinding wheels, means for mounting said grinding wheels to rotate about axes fixed with respect to one another beneath said conveyor means, means for normally maintaining said platform in substantially horizontal alignment with said conveyor means, and means for lowering the said platform to bring two opposite corners only of the sheet into engagement with said grinding wheels to grind the said corners simultaneously. 70 75 75

2. In a machine for grinding the corners of sheets or plates of glass and the like, a vertically movable horizontal platform for supporting the sheet to be ground on edge in a vertical position, 5 horizontal conveyor means arranged at opposite sides of said platform and along which the sheet may be moved onto the platform prior to grinding and from said platform subsequent to grinding, a pair of rotatable grinding wheels, means for mounting said grinding wheels to rotate about axes fixed with respect to one another beneath said conveyor means, manually operated means for lowering said platform to bring two opposite corners only of the sheet into engagement with said grinding wheels to grind the said corners simultaneously, and spring means operable to raise the said platform into substantially horizontal alignment with said conveyor means and to maintain it in such position upon the release of said lowering means by the operator. 10

3. In a machine for grinding the corners of sheets or plates of glass and the like, a pair of rotatable grinding wheels, means for mounting said grinding wheels to rotate about horizontal axes fixed with respect to one another, a horizontal channel member arranged above said grinding wheels having a bottom and opposite side walls, the bottom of said channel member being cut away above said grinding wheels, a vertically movable platform mounted between the side wall of said channel member above said grinding wheels and adapted to support the sheet to be ground on edge in a vertical position, 15 two series of horizontally aligned conveyor rollers arranged at opposite sides of said platform and along which the sheet may be moved onto the platform prior to grinding and from said platform subsequent to grinding, manually operated means for lowering said platform to bring two opposite corners only of the sheet into engagement with said grinding wheels to grind the said corners simultaneously, spring means operable to raise said platform into substantially 20 horizontal alignment with the two series of conveyor rollers and to maintain it in such position upon the release of said lowering means by the operator, and vertical guideways provided upon the side walls of said channel member and within which portions of said platform are received 25 to guide the said platform in its vertical movements. 30

veyor rollers, means for lowering said platform to bring two opposite corners only of the sheet into engagement with said grinding wheels to grind the said corners simultaneously, and co-acting means on the platform and side walls of said channel member for guiding said platform in its vertical movements. 5

4. In a machine for grinding the corners of sheets or plates of glass and the like, a pair of rotatable grinding wheels, means for mounting 10 said grinding wheels to rotate about horizontal axes fixed with respect to one another, a horizontal channel member arranged above said grinding wheels having a bottom and opposite side walls, the bottom of said channel member 15 being cut away above said grinding wheels, a vertically movable platform mounted between the side walls of said channel member above said grinding wheels and adapted to support the sheet to be ground on edge in a vertical position, 20 two series of horizontally aligned conveyor rollers arranged at opposite sides of said platform and along which the sheet may be moved onto the platform prior to grinding and from said platform subsequent to grinding, manually operated means for lowering said platform to bring two opposite corners only of the sheet into engagement with said grinding wheels to grind the said corners simultaneously, spring means operable to raise said platform into substantially 25 horizontal alignment with the two series of conveyor rollers and to maintain it in such position upon the release of said lowering means by the operator, and vertical guideways provided upon the side walls of said channel member and within which portions of said platform are received 30 to guide the said platform in its vertical movements. 35

PETER J. KIRKMAN.
